Bradley L. Benson
ATTORNEY.

UNITED STATES PATENT OFFICE.

LAUREN T. TUTTLE, OF SAN FRANCISCO, CALIFORNIA.

COMMUTATOR.

1,347,065.

Specification of Letters Patent. Patented July 20, 1920.

Application filed June 9, 1919. Serial No. 302,960.

To all whom it may concern:

Be it known that I, LAUREN T. TUTTLE, a citizen of the United States, and a resident of the city and county of San Francisco, 5 State of California, have made a new and useful invention—to wit, an Improvement in Commutators; and I do hereby declare the following to be a full, clear, concise, and exact description of the same.

10 This invention relates to a new and useful improvement in timing mechanism commonly known as commutators.

This device is particularly adapted to be used with Ford cars, but it is obvious that 15 the same may be used in other places to accomplish similar results.

The principal object of the invention is to produce a commutator which may be cheaply manufactured and which may be 20 readily assembled, and which will afford superior ignition and longer wearing properties.

Another object of this invention is to provide a commutator which may be attached 25 to the usual Ford car without any material change.

Another object is to provide means whereby the contacts may be readily changed when worn.

30 Further objects and advantages will be seen as the description proceeds.

In this specification and the annexed drawings, the invention is illustrated in the form considered to be the best, but it is to be 35 understood that the invention is not limited to such form, because it may be embodied in other forms, and it is also to be understood that in and by the claims following the description, it is desired to cover the invention 40 in whatsoever form it may be embodied.

45 In the accompanying drawings:

Figure 1 is a plan view in elevation of the improved commutator.

Fig. 2 is a cross section on the line 2—2 of

45 Fig. 1.

Fig. 3 is a side view in elevation of a ring member.

Fig. 4 is a plan view in elevation of the same.

50 Fig. 5 is a plan view in elevation of the moving contact carrying member.

Fig. 6 is a cross section of the same taken on the line 6—6 of Fig. 5.

55 Fig. 7 is a detail view of one of the spring members.

Fig. 8 is a detail view of one of the spring contacts.

Like numerals correspond to like parts in the several views.

The numeral 6 represents the end of the 60 usual cam shaft of a Ford car having a nut 7 screwed upon its outer end. The numeral 8 refers to a bushing adapted to surround the said shaft to which is attached preferably a fiber member. This fiber 65 member 9 is provided at 11 with a metal contact piece, preferably of phosphorus bronze. This contact piece is held in engagement with the fiber member 9 through dove-tail connections as shown in Fig. 5. 70 A screw 12 is also provided which assists in retaining the metal member 11 in position and passes through the fiber member 9 and is threaded through the bushing 8. This screw 12 also forms an electrical connection between the bushing 8 and the contact 11, the bushing 8 being in contact with the cam shaft of the car, the frame of which is usually electrically grounded. Surrounding the end of the shaft is a cup member 13 80 carrying binding posts 14. These binding posts 14 are provided with the usual knurled nuts 15, and pass through the cup 13. At 16 and 17 fiber pieces are introduced so as to further assist in insulating the binding 85 posts from the cup.

The inner ends of the binding posts 14 contact with metallic plates 18 which plates are curved at their ends, as at 19, to receive the ends of springs 21. These springs are 90 coiled as shown in Fig. 7 and have a central loop 22 adapted to receive and engage contact members 23. These contact members are circular in shape and are provided with a groove 24 to receive the spring wire 95 forming the loop 22. By means of this construction the metal members 23 may be rotated with relation to the spring or may be laterally removed and replaced.

In assembling my device upon a Ford car, 100 the usual spring contact roller is removed and the fiber member 9 with its bushing 8 is placed in its stead upon the end of the shaft 6, after which a nail or similar object is inserted through the opening 26 (see Figs. 105 5 and 6) the purpose of which is to provide a means for placing this contact carrying member upon the shaft, so that the motor will be properly "timed."

It will be understood that this commu- 110

tator will replace other devices which have become worn or inoperative and it is of great importance to provide a structure which may be easily and quickly adjusted to the same position relative to the engine parts and preserve the pre-arranged firing cycle in order to obviate the necessity of timing the valves.

- 10 After the nail or other object has been forced into the hole in the shaft 6, a ring member 27 is placed over the end of the bushing 8 so that the cut away portion 29 will pass around the nail or alining tool, after which the nut 7 is replaced upon the shaft 6 and tightened. The nail or alining tool may then be withdrawn and the cup member placed in proper position so that the metal contacts 23 will rest upon the periphery of the member 9, and when rotated the contact 11 will be brought into successive contact with the members 23.
- 15 Having thus described my invention, what I claim as new and desire to secure by Letters Patent of the United States is as follows:—

- 20 1. In a commutator, the combination of a rotating contact, a cup shaped member adapted to inclose said rotating contact, springs mounted within said cup shaped member, and coiled in a plane tangential to that of said rotating member, and means for causing electrical connection between said springs and said rotating contact.
- 25 2. In a contact device, the combination of a movable contact member, binding posts suitably insulated and in line with said movable contact, plates in contact with the ends of said binding posts, coiled spring members provided with loops substantially
- 30 in the center of said coils and extending tangentially from said coils, said spring members having their free ends secured to

said plates and a contact member carried by each of said loops.

3. In a contact device, the combination of a movable contact member, binding posts suitably insulated and in line with said movable contact, plates carried by the end of said binding posts, coiled spring members each provided with a loop substantially in the center of said coils and extending tangentially from said coils and each having their free ends secured to said plates, and a contact member carried by each of said loops, said contacts being circular in form. 55

4. In a contact device, the combination of a movable contact member, binding posts suitably insulated and in line with said movable contact, plates carried by the ends of said binding posts, coiled spring members each provided with a loop substantially in the center of the coils thereof and extending tangentially from said coil and each having its free ends secured to one of said plates, contact members carried by said loops, said contacts being circular in form and each provided with an annular groove adapted to engage a loop on one of said coiled spring members.

5. In a commutator, the combination of a rotating contact, a cup shaped member adapted to inclose said rotating contact, coil spring members mounted within said cup shaped member, each of said coil spring members consisting of a right and left coil, 75 and means on each of said members for carrying a contact.

In testimony whereof, I have hereunto set my hand at San Francisco, California, this 3rd day of June, 1919.

LAUREN T. TUTTLE.

In presence of—

PHILIP R. FASSETT.
